PERPETUAL CALENDAR AND CURRENT DATE
INDICATOR MEANS THEREFOR

John James O'Brien, New York, N. Y.

Application June 8, 1939, Serial No. 277,968

4 Claims. (Cl. 40—110)

This invention relates to improvements in perpetual calendars and more specifically to a current date indicator means therefor.

Monthly calendars having the days thereof arranged in the usual horizontal weekly rows, makes it difficult for a person referring to the calendar to rapidly ascertain the current day. It is therefore the main object of the invention to successively frame the numbers of the days 10 of a month in a contrasting color from that of the printed numbers and back ground so that a person may from day to day reset the calendar and anyone referring thereto will have his or her attention directed to that number indicative 15 of the current day of the month.

Another feature of the invention resides in a current date indicating calendar in which a single horizontally slidable indicating element is employed for successively color framing the days 20 of a month.

Another feature of the invention is to provide a monthly calendar in which the numbers indicative of the days of a month are each framed by four spaced openings with which a colored indicator slide is associated, the color on the indicating slide being of a contrasting color from that of the face of the calendar and calendar numbers, whereby when the indicator slide is 25 adjusted relative to any set of framing openings, the numeral surrounded by the openings will be framed by the contrasting color of the indicator slide showing through the set of slots. The colored area of the indicator slide is so arranged that it will only register with a single set of 30 framing openings at one setting so as to avoid any confusion which would occur if the colored area should register with any openings other than those framing the number of the current day.

40 A further feature of the invention is to provide a current day indicating perpetual calendar which is simple and inexpensive of construction, easy to set to a current month and from day to day for successively color framing the days of a month, and which is attractive in appearance to enable the placing of the same upon a desk without detracting from the furnishings thereof.

Other features of the invention will become 50 apparent as the following specification is read in conjunction with the accompanying drawing, in which:

Figure 1 is a perspective view of the perpetual calendar illustrating the same as set for the 26th 55 day of the month of May.

Figure 2 is an enlarged vertical transverse sectional view on the line 2—2 of Figure 1.

Figure 3 is an enlarged fragmentary horizontal sectional view on the line 3—3 of Figure 1.

Figure 4 is a detail perspective view of the 5 pack of monthly calendar cards.

Figure 5 is a detail perspective view of the pack of the name of the month cards.

Figure 6 is a front elevational view of the indicator slide member. 10

Figure 7 is a perspective view of the indicator slide member.

Figure 8 is a fragmentary front elevational view of a calendar card superposed over the colored areas of the indicator slide element to illustrate the manner in which the colored areas 15 register with only four related framing openings.

Referring to the drawing by reference characters, the numeral 10 designates my improved perpetual calendar in its entirety which includes 20 a rearwardly inclined panel 11 having a substantially rectangular shaped window opening 12 therein which imparts to the panel a frame appearance. The panel 12 is illustrated as being constructed of sheet metal and formed integral 25 therewith and extending rearwardly from the bottom edge thereof is a flat base 13. The base 13 and panel 11 are disposed at an angle which is less than a right angle so that when the base 13 is resting upon a flat support, the panel 11 30 will assume a rearwardly inclined upstanding position.

Fitting against and supported at the rear side of the panel 11 is a card storage pocket rack 14. The rack 14 is U-shape in cross section and includes a rear wall 15, forwardly extending end walls 16—16, and outwardly extending flanges 17—17 integral with the front edges of the end walls. The flanges 17—17 fit flat against the rear of the panel 11 beyond the ends of the window opening 12 and are respectively lapped and held by rearwardly and inwardly bent flanges 18—18 formed integral with the side ends of the panel 11. The walls 15, 16—16 coact with the rear of the panel 11 to define the pocket rack 14 40 for the reception of calendar and name of the month cards hereinafter to be described.

Slidably disposed within the pocket rack 14 just inwardly of the plane of the panel 11 is an indicator slide member 19 constructed from a 50 single blank of flat metal and which comprises a flat rectangular body portion 20. The lower portion of the blank is bent rearwardly and thence forwardly upon itself to provide a flat rearwardly extending base 21. After forming the 55

base 20 the lower portion of the blank of metal is bent upwardly in spaced relation to the flat body portion 20 to provide a relatively low front wall 22, and extending forwardly from the top of the wall 22 is a finger manipulating element 22. The bottom edge of the wall 15 terminates closely adjacent the base 13 and base 21 extends rearwardly therebetween. The manipulating element 23 extends forwardly through the window opening 12 just above the bottom edge thereof. By reason of the construction hereinbefore described, it will be understood that the indicating member 19 is captively associated with the panel 11 and pocket rack 14 and may be slid horizontally from one end of the window opening to the other, the back and forth sliding movement being limited by contact of the side edges of the body portion 20 with the end walls 16-16 as best seen by reference to Figure 3.

20 The body portion 20 of the indicating slide member 19 is provided with two suitably spaced identical zig-zag colored areas 24-24. The colored areas 24-24 are disposed side by side and they are illustrated as red in color so as to be of a contrasting color from that of the calendar cards and printed calendar indicia appearing thereon. Each colored area 24 consists of four connected intermediate successively stepped rectangular shaped colored sections 25, and two reduced tail end sections 26-26. The reason for this shape and arrangement of the colored areas 24-24 will be further appreciated hereinafter.

25 In Figure 4 of the drawing, I have illustrated a set of monthly calendar sheets or cards, there being four of such cards to the set and each designated by the numeral 27. Seven monthly calendar cards are needed, but the reverse side of three cards are utilized and the fourth card has but one calendar month printed on but one side. Seven monthly calendars are required to meet the condition that the first day of a current month may fall on either of the seven days of a week, that is, either Sunday, Monday, Tuesday, Wednesday, Thursday, Friday, or Saturday.

30 The calendar cards 27 are of a size to freely slide into and out of the pocket rack 14 and printed upon the reverse sides of three of the cards 27 and upon one side of the fourth calendar card is a calendar month 28, the same being rectangular and so located on the card as to show through the window opening 12. Each calendar month 28 includes thirty-one days but provision is made to indicate the number of days in a current month containing less than thirty-one days.

35 Each of the numbers 1 to 31 which are indicative of the days of the month are boxed in by a set of four circular openings 29 which are equidistantly spaced crosswise of the card and vertically thereof so that there are six horizontal rows 40 of openings and eight vertical rows of openings 29. Each calendar card 27 is provided with a horizontally elongated slot 30 above the printed calendar month 28 and midway between the side edges of the card.

45 In Figure 5 of the drawing, there is illustrated a set of three name of the month sheets or cards, each card of the set being designated 32. Each card 32 has printed upon each side thereof, the names of two successive months of a year, each 50 name of the month being designated 33. The two names of the month appearing on each side of a card are reverse relative to each other and are so located from the edges of the card as to register with the slot 30 of a calendar card when 55 arranged in correlated position within the pocket

rack 14. Associated with the name of each month having thirty days is the numeral "30," and with the name of the month of February, there appears the numeral "28."

5 In the drawing, all of the cards 27 and 32 are white, the calendar month 28 and names of the month 33 are printed in black, and the colored areas 24-24 on the body 20 of the indicator slide member 19 are red and the remainder of the body 20 is white to match the color of the cards 27 and 32. Other combinations of contrasting colors may be used in lieu of white, black, and red if desired.

10 In Figure 1 of the drawing, I have illustrated the perpetual calendar 10 as being set for the 15 26th day of May, with the first day of May appearing on a Monday, as occurred during the year of 1939. To set the calendar to this date, the calendar card 27 having the calendar 28 on which the first day appears on Monday is slid 20 down into the rack pocket 14 to lie forward of the body 20 of the indicator member 19, the lower portion of the card fitting between the body 20 and the wall 22. The operator next picks a card 25 32 containing the name of the current month, and in this instance the selected card contains the word "May." The selected card 32 is now placed at the front of the remainder of the cards 32 and 27 and holding them in pack form, they are inserted downwardly into the pocket rack 14 30 behind the body 20 of the indicator member 19, and when the lower edges of the cards seat upon the flange 21, the word "May" registers with the slot 30 in the forwardly disposed selected calendar card 27. Starting with the first day of a 35 current month, the operator grasps the finger piece 23 and slides the slide indicator member 19 to cause the colored areas 24-24 to register with the set of four openings 29 which frame the numeral "1." In this position of the indicator 40 member, the top tail sections 26-26 of the colored areas 24-24 respectively register with the two uppermost openings 29 and portions of the next lower sections 25-25 register with the lower openings 29 of this set of four. As the 45 days of the month pass, the slide indicator member is successively moved back and forth to cause sections of the colored areas to register with the sets of framing openings 29. In Figure 1 of the drawing, the indicator slide member is set so that 50 portions of the colored areas 24-24 register with the set of four opening 29 which frame the "26" day of the month. The relative position of the colored areas 24-24 with respect to the openings 29 in the calendar card is clearly shown in Figure 55 8. It will be noted that when the indicator member is properly adjusted, the two pairs of vertically aligned openings of each set expose portions of the colored areas 24-24 and that no other portions of the colored areas are exposed 60 through any of the other openings 29. Thus four red colored dots frame the current day and a person referring to the calendar may readily detect the current day of a month for his or her eyes will be led to these colored framing dots. 65

By removing the cards 27 and 32 from the pocket rack and rearranging them, all of the calendar months of a year may be successively displayed, for in selecting the calendar card 27 to be displayed, it is only necessary to know the day 70 of the week that the first day of a current month appears. Thus, the calendar is perpetual and may be used for an indefinite period of time.

While I have shown and described what I consider to be the preferred embodiment of my 75

invention, I wish it to be understood that such changes in construction and design as come within the scope of the appended claims may be resorted to if desired without departing from the spirit of my invention.

Having thus described the invention, what I claim as new and desire to secure by Letters Patent of the United States, is:

1. In a calendar, a calendar sheet having the numerical days of a calendar month arranged on the front thereof, each numerical day being framed by a set of openings provided in said sheet, a member mounted for horizontal back and forth sliding movement at the rear of said calendar sheet, and a pair of spaced color indicating areas on the front side of said member of a contrasting color from that of said calendar sheet for selective registration with a set of frame openings of any numerical day appearing on the calendar sheet by manually sliding said member to a set position relative to said calendar sheet.

2. In a calendar, a fixed calendar sheet having intersecting horizontal and vertical rows of numbers indicative of the days of a month on the front side thereof, said calendar sheet having intersecting horizontal and vertical rows of openings therein, the intermediate intersecting horizontal and vertical rows of openings being interposed between the respective intersecting horizontal and vertical rows of numbers whereby each number is framed by a set of four openings, a member mounted for horizontal sliding movement at the rear of said calendar sheet, and spaced color indicating means on the front side of said member of contrasting color from that of said calendar sheet for selective registration with any one set of four openings by sliding said member to a set position relative to said calendar

sheet to facilitate the color framing of the current day of a calendar month, said color indicating means comprising a pair of spaced identically shaped colored areas arranged side by side, each colored area consisting of a series of connected stepped colored sections, substantially as and for the purpose specified.

3. In a calendar, a frame, a calendar sheet mounted in said frame having horizontal rows of vertically aligned numbers on the front thereof indicative of the days of a calendar month, said calendar sheet having horizontal and vertical intersecting rows of spaced perforations therein which frame the respective numbers, an indicator member slidably mounted in said frame including a flat body disposed rearward of said calendar sheet, and a pair of spaced identically zig-zag shaped colored areas arranged side by side upon the front of said body for registration with the perforations framing any selected number, said colored areas being of a color in contrast to that of the sheet and numbers contained thereon.

4. In an article of the class described, a fixed panel member having spaced vertical and horizontal intersecting rows of perforations, individual reference indicia provided on the front of said panel member and respectively disposed between the intersecting rows of perforations and boxed thereby, a flat member slidably mounted rearward of said panel member, and a pair of spaced step-shaped colored areas provided on the front side of said flat member for selective registration with those perforations which box any one of the individual reference indicia, said colored areas being of a contrasting color than that of said panel member and reference indicia.

JOHN JAMES O'BRIEN.
